UNITED STATES PATENT OFFICE.

ALFRED M. LANE, OF ST. LOUIS, MISSOURI, ASSIGNOR TO MONARCH METAL PRODUCTS COMPANY, OF ST. LOUIS, MISSOURI, A CORPORATION OF MISSOURI.

WOODWORKING MACHINE.

Application filed November 7, 1924. Serial No. 748,307.

My invention relates to woodworking machines particularly adapted for use in altering window sashes and doors to permit the application of weather strips thereto. Heretofore such altering, which consists in surfacing, leveling, grooving, and rabbeting portions of the window sash, has been performed by skilled workmen with the use of hand tools. The principal objection to this method of altering the window sashes is that it requires considerable time and is quite expensive.

One of the principal objects of the present invention is to produce a small and compact power driven woodworking machine, which can be easily transported from place to place and which will easily and cheaply perform upon the sashes or door the plurality of operations required for the installation of weather strips. Other objects are simplicity and cheapness in construction.

The invention consists principally in the improved woodworking machine hereinafter shown and described; and it also consists in the combinations and arrangements of parts hereinafter described and claimed.

In the accompanying drawings, which form part of this specification and wherein like symbols refer to like parts wherever they occur,

Fig. 1 is a plan view of a woodworking machine embodying my invention;

Fig. 2 is a side elevation of said machine;

Fig. 3 is a rear elevation thereof;

Fig. 4 is a vertical cross-section taken through the machine along the cutter shaft on the line 4—4 in Fig. 1;

Fig. 5 is a vertical longitudinal section, the section being taken along the opening through the middle of the work supporting table on the line 5—5 in Fig. 1;

Fig. 6 is a horizontal section through one of the end cutter guards; and

Fig. 7 is an enlarged side elevation of one of the spring-pressed guide rollers.

Referring to the accompanying drawings, my woodworking machine comprises a box-like housing or frame 10 which is supported at its four corners by leg members 11. The box-like housing 10 is provided at its top with a forwardly extending table portion 12 adapted to support the work. The work supporting table has a narrow opening 13 extending vertically therethrough from end

to end thereof; and it is also provided immediately above the box-like supporting body with openings that are closed by cover plates 14. Located beneath the cover plates 14 is a horizontal shaft 15, whose ends are journaled in suitable bearings 16 at opposite sides of the housing 10.

The cutter shaft 15 has different forms of cutter heads secured thereto: namely, a rabbeting head 17, a grooving head 18, a narrow jointing head 19, and a wide jointing head 20.

The cutter shaft 15 extends through openings provided therefor in the side walls of the housing 10 and is provided at one end with a cutter head 21 and at its other end with a cutter head 22.

The chief difference between the cutter heads 17, 18, 19, and 20 and the end cutter heads 21 and 22 is that in the former the bits or blades are carried upon the peripheral surface of the head and are adapted to engage the under surface of the work, whereas in the latter the bits or blades are carried upon the end surface of the head and are adapted to engage the side of the work.

The end cutters 21 and 22 have side and end cutting edges; and the cut is made by first pressing the side of the work against the cutter, which bores its way out of the side of the work, after which the work is moved transversely of the cutter, which, by cutting on its side, extends the cut to any desired length.

The cutter heads 17, 18, 19, and 20 work in openings provided therefor in the cover plates 10 and are arranged so that the cutting edges pass above the plane of the work supporting table so as to engage the under surface of the work as it is moved with reference to said cutters.

In this connection, it is noted that the cover plates are removably secured in position by means of screws 23, thus giving free access to inspect, repair, or sharpen the cutters.

The cutter shaft 15 is permanently geared to the driving shaft 24 of an electric motor 25 by means of a sprocket chain 26, whereby said shaft rotates continuously. As shown in the drawing, the electric motor is supported on a bracket 27 secured to the housing 10.

The sprocket chain is provided with a suitable guard or casing 28 for preventing injury to the workmen by contact with said chain. The cutter heads 17, 18, 19, and 20 are provided with guards 29 which serve

to prevent injury to the workmen by contact with the cutting edges of said cutter heads. Each of these guards comprises a semi-circular plate having a hub portion sleeved on the cutter shaft and an arcuate outer flange or hood portion adapted to overlap the upper portion of the cutter head.

The forward end portion of the arcuate flange of each cutter head is provided with a curled portion 30 adapted to abut against the forward end of the cutter openings in the cover plates. The cutter guards are normally yieldably held with their hood portions covering the upper portions of the cutters by means of coil springs 30^a, one end of a spring being secured to the rear wall of the hollow housing and the other end being secured to the lower portion of a cutter guard. The curled upper end portions of the cutter guards 29 project above the work supporting table and are adapted to be swung rearwardly below the surface of the table when engaged by the work. The end cutters 21 and 22 are also provided with cutter guards 31. Each of these end cutter guards comprises a spring-pressed cuplike member 32 which fits over the end cutter and normally projects beyond the cutting edge thereof, thereby preventing injury to the workmen by contact with the cutter. The end cutter guards are slidably supported on pins 33 (see Fig. 6) that are threaded into the side walls of the housing 10 and are adapted to extend into holes provided therefor in the cutter guards. The end cutters overlap the outer ends of the cutters and are normally held in said position by means of coil springs 33^a sleeved on one of each pair of supporting pins 33, which pin is provided with a head portion which serves to limit the outward sliding movement of the end cutter guard. The end cutter guards are provided with forwardly projecting horizontal finger portions 34 that are curved inwardly thereby forming cam surfaces, which, when engaged by the work, cause said cutter guards to move inwardly and thus permit the cutting edges thereof to engage the side of the work.

The work that is to be engaged by the end cutters is supported on horizontally disposed plates 34^a located below the end cutters on opposite sides of the housing 10. These plates are supported for horizontal sliding movement in directions transverse to the axes of the end cutters in slideways 35 formed in the horizontally extending portion of bracket members 36 and 37 secured to the side walls of the housing. The bracket member 36, which supports the table slide 40 located adjacent to the end cutter 21 at the left-hand side of the machine, is bolted or otherwise immovably secured to the side walls of the box-like housing. The bracket 37, which supports the table slide located adjacent to the end cutter 22 at the right-

hand side of the machine, has a slot and bolt connection 38 with the side wall of the hollow housing, the slots extending vertically, whereby said bracket member is adapted for vertical adjustment to vary the height of the 70 slide plate with relation to the end cutter. This vertical adjustment of the vertically adjustable table bracket 37 is accomplished by means of a vertically disposed screw 39 which is threaded through a bracket 40 secured to the side wall of the housing beneath the bracket 37. The upper end portion of the screw 39 projects through a hole in the bracket 37; and endwise movement of said screw with relation to the bracket is prevented by means of collars 41 that are pinned to the screw above and below the bracket. The adjusting screw 39 is manipulated to raise and lower the slide plate carried by the bracket 37 by means of a hand wheel 42 secured to the lower end of said adjusting screw.

The work is yieldably held in contact with the end cutters by means of pressure pads 43 located opposite said cutters. The pressure pads rest flatwise on the outwardly extending flanges of brackets 44, whose depending flanges are rigidly secured to the outer faces of the table slides. These pressure pads comprise rectangular blocks having slot and screw connections 45 with the brackets 44 adapted to permit horizontal sliding movement of said blocks towards and away from the end cutters. The inner marginal portions of these pressure blocks are provided with a multiplicity of spring teeth 46 adapted to yieldably engage the outer side face of the work and hold the same in contact with the end cutters. The pressure pads are adjusted towards and away from the end cutters by means of adjusting screws 47 that are threaded through the upstanding flanges of the supporting brackets for said pressure pads.

The machine is provided adjacent to each of the cutter heads with upper and lower work guides capable of being lengthened or shortened. Each of these guides comprises two telescoping U-shaped tubular members 48 and 49 whose horizontally spaced parallel branch portions are adapted to slide one within another. The upper and lower telescopic members are arranged with their respective branches one above the other, the outer branches serving as guides for work engaged by the end cutter head 22 and the inner branches serving as guides for work engaged by the cutter head 20. Both branches of the outer tubes 48 of the upper and lower guide members extend through openings provided therefor in blocks 50 that are sleeved on posts 51 which are held in vertical openings at the front and rear corners of the table by thumb screws 52. The lower blocks rest on the table; and the upper blocks

may be adjusted vertically on their supporting posts and locked in the desired adjusting position by means of set screws 53.

The guide rails for the work engaged by the grooving head 18 comprise two pairs of telescopic tubes 54 and 55 arranged one above the other over the opening 13 which extends from end to end of the table. The outer members 54 of each pair of telescoping guides are mounted in vertically spaced blocks secured to uprights 56. The blocks 57 that support the lowermost work guide 54 rest on the work supporting table and have a sliding fit in rectangular notches 59 located in one side wall of the opening 13 which extends from end to end of the table. The purpose of the opening is to accommodate work having a shouldered surface, as shown in Fig. 4. The blocks 57 are provided with shouldered portions that overlap the upper and lower edges of the table and thus prevent vertical movement of said blocks. The blocks are adjusted horizontally in directions crosswise of the table by means of an adjusting screw 60 that engages the slide lock at the rear end of the table. This adjusting screw is journaled in a horizontal opening in a lug 61 that projects horizontally from the rear end of the table; and collars 62 are secured to said adjusting screw on opposite sides of said lug to prevent endwise movement of the screw thereon. The adjusting screw engages a threaded hole in a boss of lug 63 that projects rearwardly from the slide block. By manipulating this adjusting screw, the work guides formed by the telescoping guides 54 and 55 may be adjusted crosswise of the table to accommodate work of different widths. The blocks 64 which support the upper tubes are slidable on their supporting standards 56 and are held in the desired position by set screws 65. The machine is also provided with upper and lower work guides for defining the path of the work moving with relation to said guides and the shaping cutters 21 and 17. The upper guides comprise telescoping U-shaped tubes 66 and 67, whose branches are arranged in the same horizontal plane and are supported adjacent to the front and rear corners of the machine by means of blocks 68. The blocks are slidably mounted on posts 69 that project upwardly from the table and are held in the desired position by set screws 70. The inner branches of the telescoping tubes serve as guides for the work engaged by the cutter head 17; whereas the outer branches of said guides serve as a guide for the work engaged by the end cutter 21. The lower guard for the work engaged by the cutter head 17 comprises a metallic bar 71; and the lower guard for the work engaged by the end cutter 21 comprises two telescoping tubes 72 and 73 located below the outer branches of the telescopic

guide tubes or rails 66 and 67. The lower telescopic work guides 72 and 73 are supported at the front and rear corners of the machine by blocks 74 slidably on the posts 68 that slidably support the supporting blocks 69 for the upper work guides 66 and 67.

The work is yieldably held in contact with the work guides by means of spring-pressed pressure guides or rollers 75. As shown in Fig. 7, each of the pressure guides comprises a hub portion 76, a bifurcated outer end portion 77 that rotatably supports the roller 75, and a spring 78 connecting said hub and bifurcated outer end portion. The hub portions of the pressure guide are mounted for horizontal swinging movement on vertical studs 79 that project upwardly from the work table. The contacting faces of the hub portions of the pressure devices and the work table are provided with interfitting V-shaped grooves and ridges; and the upper ends of the studs are provided with thumb nuts 80, whereby said devices may be locked in the desired position. By this arrangement the rollers may be adjusted towards and away from the work and are adapted to form and serve as pressure devices for yieldably holding the work in contact with the work guides. One of these pressure devices is located in front of the cutter head 19 and is arranged to bear against the upper surface of the work and thus hold the same down on the cutter.

Projecting from the rear corners of the machine are brackets 81 adapted to slidably support horizontal tubes or rods 82, one end of which is located in the plane of the lower work guides. These rods or tubes extend rearwardly and are supported in blocks 83 on the ends of the slideable sections of the lower work guides. Posts 84 project upwardly from the blocks 83 and slidably support blocks 85, which, in turn, support the slideable section of the upper work guides. The blocks 85 are adjustable up and down on the posts 84 and are locked in the desired position by set screws 86. Located below and extending transversely of the work guides is a cross tube 87 which is supported at its opposite ends by brackets 88 slidably mounted on the tubes 82. A similar rod 89 is supported in portions that depend from the blocks 83. The rods 87 and 89 are provided with upstanding brackets 90 having bifurcated outer end portions between which are journaled rollers 91. These rollers are disposed with their upper surfaces on a level with the top surface of the work supporting table and with their axes disposed transverse to the direction in which the work travels and thus constitute roller supports for the work as it leaves the table.

The operation of the machine is as follows: When it is desired to operate upon the side

of the work, such, for instance, as the side faces of the meeting rails of the upper and lower sashes of a window, end cutters of a shape necessary to perform the desired operation are secured to the ends of the cutter shaft, and the pressure blocks 43 are then adjusted to hold the work against the work guides. The sashes may then be placed on the slide plates 34^a in an upright position and moved transversely of the end cutters which engage the side of the sash and make the desired cut. When it is desired to rabbet, groove, or surface an edge of the sash, the sash is placed on the table in line with the desired cutter head and the spring rollers adjusted to hold it against the work guides therefor. The work is then slid along the table into engagement with the cutter head which performs the desired operation.

It is obvious from the foregoing description that my woodworking machine is very simple in construction; that it can be readily transported from place to place; that it is adapted to quickly and accurately perform upon the sashes, either simultaneously or independently, the operations desired; and that it can be quickly adjusted to accommodate work of different shapes and sizes.

Obviously the hereinbefore described machine admits of considerable modification without departing from the invention; therefore, I do not wish to be limited to the exact details of construction shown and described.

What I claim is:

1. A woodworking machine comprising a work support, a rotary cutter journaled thereon, and work guides comprising telescoping members mounted on said work support and extending transversely of the axis of said cutter.

2. A woodworking machine comprising a work supporting table having a plurality of openings therein, a cutter shaft rotatably supported beneath said openings, a plurality of rotary cutters mounted on said shaft, and a plurality of horizontal work guides mounted on said table adjacent to said cutters and extending transversely of said cutter shaft, each of said guides comprising two telescoping tubular members.

3. A woodworking machine comprising a work supporting table having a plurality of openings therein, a cutter shaft rotatably supported beneath said openings, a plurality of rotary cutters mounted on said shaft, a plurality of horizontal work guides mounted on said table adjacent to said cutters and extending transversely of said cutter shaft, each of said guides comprising two telescoping tubular members, and means for adjusting said members vertically.

4. A woodworking machine comprising a work supporting table having a plurality of openings therein, a cutter shaft rotatably

supported beneath said openings, a plurality of rotary cutters mounted on said shaft, a plurality of horizontal work guides mounted on said table adjacent to said cutters and extending transversely of said cutter shaft, each of said guides comprising two telescoping tubular members, and a plurality of work supporting rollers carried by the inner telescoping members.

5. A woodworking machine comprising a work supporting table having a plurality of openings therein, a cutter shaft rotatably supported beneath said openings, a plurality of rotary cutters mounted on said shaft, a plurality of horizontal work guides mounted on said table adjacent to said cutters and extending transversely of said cutter shaft, each of said guides comprising two telescoping members, a plurality of work supporting rollers carried by the inner telescoping member, slide rods supported at one end by the inner telescoping members of said work guides, brackets secured to the table and slidably supporting the other ends of said slide rods, and a plurality of work supporting rollers mounted on said slide rods and movable longitudinally thereof.

6. A woodworking machine comprising a work supporting table having a plurality of openings therein, a cutter shaft rotatably supported beneath said openings, a plurality of rotary cutters mounted on said shaft, a plurality of horizontal work guides mounted on said table adjacent to said cutters and extending transversely of said cutter shaft, each of said guides comprising two telescoping members, a plurality of work supporting rollers carried by the inner telescoping member, slide rods supported at one end by the inner telescoping members of the work guides located adjacent to the sides of the table, brackets secured to the table and slidably supporting the other ends of said slide rods, a plurality of work supporting rollers mounted on said slide rods and movable longitudinally thereof, and means for adjusting one of said work guides longitudinally of the cutter shaft.

7. A woodworking machine comprising a work supporting table having a plurality of openings therein, a cutter shaft rotatably supported beneath said openings, a plurality of rotary cutters mounted on said shaft, a plurality of horizontal work guides mounted on said table adjacent to said cutters and extending transversely of said cutter shaft, each of said guides comprising two telescoping members, a plurality of work supporting rollers carried by the inner telescoping member, slide rods supported at one end by the inner telescoping members of the work guides located adjacent to the sides of the table, brackets secured to the table and slidably supporting the other ends of said slide rods, a plurality of work supporting rollers

mounted on said slide rods and movable longitudinally thereof, and means for adjusting one of said work guides longitudinally of the cutter shaft, said means comprising an adjusting screw journaled in said table and operatively engaging said last mentioned work guides.

8. A woodworking machine comprising a work supporting table having a plurality of openings therein, a cutter shaft rotatably supported beneath said openings, a plurality of rotary cutters mounted on said shaft, a plurality of horizontal work guides mounted on said table adjacent to said cutters and extending transversely of said cutter shaft, each of said guides comprising two telescoping members, a plurality of work supporting rollers carried by the inner telescoping member, slide rods supported at one end by the inner telescoping members of the work guides located adjacent to the side of the table, brackets secured to the table and slidably supporting rollers mounted on said slide rods and movable longitudinally thereof, means for adjusting one of said work guides longitudinally of the cutter shaft, said means comprising an adjusting screw journaled in said table and operatively engaging said last mentioned work guides, a plurality of spring-pressed rollers mounted on said table and adapted to hold the work to the work guides, and means for locking said rollers in the desired position of adjustment.

9. A woodworking machine comprising a work supporting table having a plurality of openings therein, a cutter shaft rotatably supported beneath said openings, a plurality of rotary cutters mounted on said shaft, a plurality of horizontal work guides mounted on said table adjacent to said cutters and

extending transversely of said cutter shaft, each of said guides comprising two telescoping members, a plurality of work supporting rollers carried by the inner telescoping member, slide rods supported at one end by the inner telescoping members of the work guides located adjacent to the side of the table, brackets secured to the table and slidably supporting rollers mounted on said slide rods and movable longitudinally thereof, means for adjusting one of said work guides longitudinally of the cutter shaft, said means comprising an adjusting screw journaled in said table and operatively engaging said last mentioned work guides, a plurality of spring-pressed rollers mounted on said table and adapted to hold the work to the work guides, and means for locking said rollers in the desired position of adjustment.

10. A woodworking machine comprising a work support, a rotary cutter mounted thereon, horizontal work guides extending transversely of the cutter axis, said work guides being extendible in the direction of their length, and work supporting rollers carried by the extendible portion of said work guides.

11. A woodworking machine comprising a work support, a rotary cutter journaled thereon, and horizontal work guides comprising telescoping members mounted on said work support adjacent to said cutter, said work guides being adjustable longitudinally and transversely of the cutter axis.

Signed at St. Louis, Missouri, this 3rd day of November, 1924.

ALFRED M. LANE.
